UNITED STATES PATENT OFFICE.

CONRAD ROSINE, OF CHICAGO, ILLINOIS.

LUBRICATING APPARATUS.

Application filed December 17, 1924. Serial No. 756,425.

This invention relates to lubricating apparatus and its principal object is to provide power multiplying means in a lubricating apparatus, whereby oils, greases or other lubricants may be forced between parts which require lubrication, with the application of considerably less force than is required with the common and well known lubricating apparatus. Another object is to provide a lubricating apparatus having certain novel characteristics, whereby it may be adapted for use as a stationary oil or grease cup. Another object is to provide a lubricating apparatus having novel power multiplying means, and provided with a flexible connection and novel means for readily attaching the flexible connection to a nipple of the type usually provided on machinery, bearings, joints and so forth. Another object is to provide a container for lubricant having a tapered discharge and terminating in a pressure cylinder having a bore of reduced diameter through which the lubricant is forced under great pressure by a plunger to the part to be lubricated. Another object is to provide in the chamber of such a lubricating apparatus a spring pressed supply plunger for supplying lubricant to said pressure cylinder whenever the plunger is withdrawn therefrom.

With these and other objects and advantages in view, this invention consists in the several novel features hereinafter fully set forth and claimed.

The invention is clearly illustrated in the accompanying drawings, in which:

Fig. 1 is a central, longitudinal section through a lubricating apparatus embodying one form of the present invention; Fig. 2 is a horizontal section taken on line 2—2 of Fig. 1; Fig. 3 is a fragmental view, partly in side elevation and partly in vertical section of the upper part of the apparatus, the view being taken in the direction of the arrow 3 in Fig. 1; Fig. 4 is a fragmental side elevation showing the means of connection between the cap and barrel or container; Fig. 5 is a detail end view of the coupling member for the end of the flexible connection; Fig. 6 is a central, longitudinal section through a slightly modified form of the invention; Fig. 7 is a central, longitudinal section illustrating the application of the invention to a stationary grease or oil cup, and Fig. 8 is a view, partly in section, and partly in side elevation of the cap shown in

Fig. 7 and parts connected therewith. Figs. 7 and 8 are made upon an enlarged scale for the purpose of clarity in illustrating the invention.

Referring to said drawings and first to Figs. 1 to 5 inclusive, which illustrate the preferred embodiment of the invention, the reference character 10 designates a barrel or container of cylindrical form, having a tapering discharge end 11 secured thereto in any suitable manner. Secured to the small end of the part 11 is a pressure cylinder 12 which contains a bore or chamber 13 of reduced diameter and beyond said bore 13 the member 12 is formed with a cavity in which is contained a spring pressed check valve 14 which seats against a seat surrounding the end of the bore 13.

The other end of the barrel 10 is open and is closed by a cap or closure 15, which, if desired, may be secured to the barrel by pin and bayonet slot connections 16, 17, (see Fig. 4) to facilitate the ready attachment of the cap to the barrel and its removal therefrom.

Associated with the cap 15 is a compression plunger 18, which is arranged in alignment with the bore 13 and is adapted to be forced thereinto to discharge the contents thereof under pressure. The compression plunger 18 may be formed as a part of or may be rigidly secured in a stem 19 of somewhat larger diameter than the plunger proper 18, and said stem and plunger are operatively connected to a handle 20 located exterior of the cap, whereby said plunger may be forcibly moved into the bore 13 and retracted therefrom.

In its preferred form the handle has a sleeve 21 rigidly secured to it, which sleeve is rotatively mounted in the cap 15, and receives one end of the plunger stem 19, which is arranged to reciprocate therein. One or more cam faces or inclined planes 22 are provided between the cap and plunger stem 19 for effecting endwise movement of the plunger in one direction, and as shown in the preferred form, the cam faces or inclined planes are provided upon the under side of an annular cam or cylindrical wedge 23, which is rigidly secured to the cap 15 as for instance by rivets as shown. Traveling along said cam faces or inclined planes are rollers 24 which are rotatively secured on a pin 25, that is secured in the plunger stem and projects through slots 26 formed in the sleeve 21. Said slots 26 extend lengthwise of the

sleeve and permit the pin 25 to travel with the plunger stem when the latter is moved endwise of itself. The stem 19 is formed with a key way 19^x, and the sleeve 21 has a 5 pin 21^x secured therein which enters the key way and prevents disconnection between the sleeve and stem. The edges of the slots engage the pin and transmit power from the handle to the plunger stem whenever the 10 handle is rotated. Two cam faces 22 are illustrated, each extending through an arch of approximately 180 degrees and one arranged diametrically opposite the other. With this arrangement, the handle 20 may 15 be turned through an arc of 180 degrees, starting from the place where the rollers are at the low places on the cam faces, thereby causing said rollers and therewith the pin 25, plunger stem 19 and plunger 18 to move 20 endwise toward the discharge end of the apparatus, the plunger entering the bore 13 and forcing out therefrom the lubricant contained therein, and under high pressure. When the rollers 24 pass the high places on 25 the cams they are returned to the low places thereon by means which will now be described.

When fully retracted, the plunger 18 uncovers the inlet port to the bore 13, permitting 30 lubricant to flow therewith. The check valve 14 prevents leakage of lubricant past the seat. When heavier oil or grease or lubricant having a high viscosity is used, means are provided for feeding the lubricant 35 to the entrance or port to the bore 13. In the form illustrated, a supply plunger 40 is used, which plunger may be in the form of a centrally apertured disc that fits the bore of the barrel 10, and is movable lengthwise 40 on the plunger stem 19. A coiled compression spring 27 is confined under compression between the plunger 40 and a shoudered sleeve 27^x below the pin 25 and said spring serves to force the supply plunger 45 40 against the lubricant contained in the barrel, thereby continuously forcing the lubricant toward the discharge end. Whenever the port to the bore 13 is uncovered, a quantity of the lubricant is forced into the 50 bore.

A pin 28 limits the movement of the supply plunger on the stem 19. The spring 27 also acts to retract the compression plunger when the rollers pass the high places of the 55 cam faces. It also acts to continuously hold the rollers against the cam faces and to keep the cap and all moving parts associated with it, together, as a unit, whereby when the cap is detached from the barrel, the stem 19, pin 60 25, rollers 24, spring 27 and supply plunger 49 are thereby removed from the barrel in their assembled condition.

The lubricating apparatus which has been described in detail is usually provided with 65 some kind of connection for connecting it to

the part which is to be lubricated. In the form of the invention illustrated in the drawing, an armored flexible tubing 29 is employed which tubing is provided with the usual threaded fitting 30 which is secured 70 upon the threaded end of the cylinder member 12. To provide a tight joint between the member 12 and tubing the rubber tubing is drawn up tightly against the end of the threaded portion 31 of the member 12 as 75 is clearly seen in Fig. 1.

The parts to be lubricated are provided with coupling nipples 32 as usual, and the free end of the flexible connection 29 is provided with a pair of spring pressed dogs 33 80 that are adapted to engage shoulders 34 on the nipple to prevent disconnection between the flexible connection and nipple when the lubricant is being forced to the bearing or joint which is to be lubricated. Said dogs 33 are shown as pivotally mounted upon a sleeve like member 35 which is permanently secured to the end of the flexible connection 29. The dogs 33 are provided with springs 85 for normally holding them in engagement with the shoulders of the nipple, and finger pieces are provided upon said dogs whereby they may be readily disengaged from the shoulders to disconnect the flexible coupling 90 from the nipple. The rubber tubing of the flexible connection may be so arranged that it bears against the end of the nipple when the flexible connection is attached thereto, thereby preventing leakage at this point. The flexible connection may be attached to 100 the nipple by simply pressing the end of the member 35 against the end of the nipple, the dogs being automatically spread apart as they pass the nipple.

In the modified form illustrated in Fig. 105 6 the plunger stem 19^a protrudes through the cap 15^a and has a handle or knob 20^a upon its outer end by which the plunger may be forced against a supply of lubricant contained in the bore of the cylinder member 12^a. The compression spring 27^a in this case bears against a pin 25^a secured in the plunger stem and also bears against the supply plunger 40^a. In this case it will be observed that the cam arrangement is dispensed with and that power is applied directly to the handle or knob of the plunger stem. In other respects the parts may be constructed substantially like those illustrated in connection with the preferred 110 form. The lubricant is fed to the port of the bore in the member 12^a, by the supply plunger 40^a as in the preferred form and is discharged therefrom by the plunger 18^a whenever the latter is forced into said discharge passage.

In the form of the invention illustrated in Figs. 7 and 8, it is applied to a stationary grease or oil cup such as is used in connection with bearings, joints and the like. 130

- Such grease or oil cups usually have a cup like barrel or container 10^b in which the grease or oil is contained, and a threaded nipple 12^b which screws into an opening 5 that leads into the bearing surfaces to be lubricated. A bore or discharge passage 13^b of relatively small diameter, is formed in the nipple 12^b and a compression plunger 18^b is slidably mounted in the cup like barrel 10^b or container 10^b and adapted to be forced into said discharge passage. The container 10^b is provided with a cap 15^b which may be secured thereon by screw threads or otherwise and rotatably mounted on the under 15 side of said cap is a cam 23^b which has cam faces or inclined planes that engage with a pin 25^b secured in the plunger stem 19^b. The cam 23^b is rigidly connected with a stem portion 21^b of the handle 20^b and turns with 20 the handle. An oil hole cover plate 20^c is provided above the cap, which cover together with the top piece of the cam 23^b rotatably secures the handle and cam to the cap. The plunger stem is guided and held 25 against rotation in a strut 19^c, and a coiled compression spring 19^a below the plunger stem acts to retract the plunger after it has been forced down to the end of its compression stroke.
- 30 It will be observed that small quantities of lubricant may be discharged under great pressure by merely turning the handle 20 of the preferred form or 20^b of the modified form shown in Figs. 7 and 8, and that when 35 the pin 25 or rollers 24 pass the high places of the cam, the compression spring serves to retract the compression plunger 18 from the bore or discharge passage 13, thereby permitting the supply plunger to again force 40 a quantity of lubricant into said bore or discharge passage.
- In the modified form shown in Fig. 6 instead of turning the handle, the knob is pressed upon, thereby forcing the plunger 45 into the bore or discharge passage and discharging the lubricant contained therein. When released the compression spring 27^a restores the plunger to its normal position and forces the supply plunger against the 50 lubricant thereby forcing a small quantity thereof into the discharge passage.
- It will therefore, be seen that the lubricant 55 may be discharged in relatively small quantities under great pressure. The apparatus is adapted for use in lubricating vehicles of all kinds, grease cups, bearings, joints, machines, in fact all mechanism where lubrication is required. It can be made to fit any 60 systems of connections of present day grease or oil cups. It can be refilled very quickly, and can be connected to and disconnected from coupling nipples in less time than others. It can be made in large or small 65 sizes for use either as a grease or oil gun, or as a grease or oil cup. It can be used with or without a flexible connection. By reason of its improved and novel construction, it has greater efficiency than the ordinary lubricating apparatus of this type. All of the parts can be quickly and easily assembled and disassembled, for any reason. The barrel is easily filled with lubricant. The device is easy to operate but very powerful in its operation.
- More or less variation of the exact details 70 of construction is possible without departing from the spirit of this invention; I desire, therefore, not to limit myself to the exact form of the construction shown and described, but intend, in the following claims, 75 to point out all of the invention disclosed herein.
- I claim as new, and desire to secure by Letters Patent:
1. In a lubricating apparatus, the combination of a barrel for containing a supply of lubricant, and having a tapered discharge end, a compression cylinder on said tapered end having a bore of reduced diameter, a compression plunger fitting said bore and 80 guided to move in said barrel and arranged to be forced into and out of said bore, means exterior of said barrel whereby said plunger is forced into said compression cylinder, a supply plunger slidably mounted on said 85 compression plunger in said barrel and a coiled compression spring cooperating with said plungers to feed lubricant to said bore of the compression cylinder, and to retract the compression plunger therefrom.
  2. In a lubricating apparatus, the combination of a barrel for containing a supply of lubricant, and having a tapered discharge end, a compression cylinder on said tapered end having a bore of reduced diameter, a compression plunger fitting said bore and 90 guided to move in said barrel and arranged to be forced into and out of said bore, a plunger actuating handle exterior of the barrel operatively connected to said plunger, a supply plunger slidably mounted on said 95 compression plunger in said barrel and a coiled compression spring cooperating with said plungers to feed lubricant to said bore of the compression cylinder, and to retract the compression plunger therefrom.
  3. In a lubricating apparatus, the combination of a barrel for containing a supply of lubricant, and having a discharge end, a compression cylinder on said discharge end, 100 having a bore of reduced diameter, a compression plunger fitting in said bore and guided to move in said barrel and arranged for movement into said bore, a plunger stem, a plunger actuating handle exterior of said 105 barrel, an arcuate cam member and a cam engaging member cooperating therewith, one being capable of rotation relative to the other, and one being operatively connected to said plunger actuating handle and the 110

other to the barrel, and a spring pressed supply plunger in said barrel for feeding lubricant to the bore of said compression cylinder, the spring of said spring pressed plunger being interposed between the compression plunger and supply plunger and operating to retract the compression plunger.

4. In a lubricating apparatus, the combination of a barrel for containing a supply of lubricant, and having a discharge end, a compression cylinder on said discharge end, having a bore of reduced diameter, a compression plunger fitting in said bore and guided to move in said barrel and arranged for movement into said bore, a plunger stem, a rotary plunger actuating handle exterior of said barrel, a stationarily mounted arcuate cam member, a cam engaging member actuated by said plunger actuating handle and secured to the plunger stem and arranged to travel on said cam member, and a spring pressed supply plunger in said barrel for feeding lubricant to the bore of said compression cylinder, the spring of said spring pressed plunger being interposed between the compression plunger and supply plunger and operating to retract the compression plunger.

5. In a lubricating apparatus, the combination of a barrel for containing a supply of lubricant, and having a discharge end, a compression cylinder on said discharge end, having a bore of reduced diameter, a compression plunger fitting in said bore and guided to move in said barrel and arranged for movement into said bore, a plunger stem, a plunger actuating handle exterior of said barrel, a stationarily mounted cam member, having oppositely arranged inclined cam faces, a pin actuated by said plunger actuating handle and secured in said plunger stem and traveling on said cam faces, and a spring pressed supply plunger in said barrel for feeding lubricant to the bore of said compression cylinder, the spring of said spring pressed plunger being interposed between the compression plunger and supply plunger and operating to retract the compression plunger.

6. In a lubricating apparatus, the combination of a barrel for containing a supply of lubricant, and having a discharge end, a

cap closing the other end of the barrel, a compression cylinder on said discharge end, having a bore of reduced diameter, a compression plunger fitting in said bore and guided to move in said barrel and arranged for movement into said bore, a plunger stem, a plunger actuating handle exterior of said barrel, and having a slotted sleeve for receiving and guiding one end of the plunger stem, a cam secured to said cap and a pin secured to said plunger stem and extending out through the slots of said sleeve and traveling on said cam.

7. In a lubricating apparatus, the combination of a barrel for containing a supply of lubricant, and having a discharge end, a cap closing the other end of the barrel, a compression cylinder on said discharge end, having a bore of reduced diameter, a compression plunger fitting in said bore and guided to move in said barrel and arranged for movement into said bore, a plunger stem, a plunger actuating handle exterior of said barrel, and having a slotted sleeve for receiving and guiding one end of the plunger stem, a cam secured to said cap and a pin secured to said plunger stem and extending out through the slots of said sleeve and traveling on said cam, a supply plunger in said barrel and having a limited movement on said plunger stem and a coiled compression spring confined between said pin and supply plunger and operating to press the supply plunger against the lubricant, and simultaneously to hold the pin in engagement with the cam.

8. In a lubricating apparatus, the combination of a barrel having a tapered discharge end, a compression cylinder on said end, and having a bore of reduced diameter, a plunger fitting said bore and mounted in said barrel for movement into said bore, a plunger stem, a cap removably secured on the open end of said barrel, a plunger actuating handle exterior of said cap, a supply plunger, pins secured in said plunger stem, one on each side of said supply plunger, and a coiled compression spring confined between said supply plunger and one of said pins, said cap, and parts associated therewith being removable from the barrel as a unit.

CONRAD ROSINE.
